UNITED STATES PATENT OFFICE.

JOHN FRANCIS BOORAEM, OF GREENWICH, CONNECTICUT, AND GABRIEL E. ROHMER,
OF RIDGEFIELD PARK, NEW JERSEY.

PLUNGE-BATH.

1,091,798.

Specification of Letters Patent. Patented Mar. 31, 1914.

Application filed December 18, 1912. Serial No. 737,434.

To all whom it may concern:

Be it known that we, JOHN FRANCIS BOORAEM, a citizen of the United States of America, residing in Greenwich, in the county of Fairfield, in the State of Connecticut, and GABRIEL E. ROHMER, a citizen of the United States of America, residing in Ridgefield Park, in the county of Bergen, in the State of New Jersey, have invented certain new and useful Improvements in Plunge-Baths, of which the following is a specification.

This invention relates to plunge-baths, and more particularly to an improved ladder or flight of steps therefor, for the purpose of facilitating entrance to and exit from the bath. Hitherto it was customary to use ladders made of iron, projecting from the wall of the bath. Such ladders were unsightly, obstructed the bath, diminished the available swimming area, and were a source of annoyance and danger to swimmers.

The object of this invention is to do away with ladders of this kind, and for this purpose the invention consists in providing in the wall of the plunge-bath terra cotta step-members having recesses therein for the purpose of enabling the bathers to use the same with hands and feet in the way that the risers of a ladder are used.

In the accompanying drawing, Figure 1 is a vertical longitudinal section through a plunge-bath equipped with our invention, Fig. 2 is a vertical transverse section through an individual step-member constructed according to the invention, Fig. 3 is a vertical longitudinal section through the member shown in Fig. 2, on line 3—3, Fig. 2, Figs. 4 and 5 are vertical transverse sections through a modified form of step-member, showing the mode of use of the same by foot and hand, respectively, Figs. 6 and 7 are respectively a front elevation of the member shown in Figs. 4 and 5, and a vertical longitudinal section of the same on line 7—7, Fig. 4, and Fig. 8 is a vertical transverse section through a form of step-member specially adapted for use at the top of the plunge-bath.

Similar numerals of reference indicate corresponding parts throughout the views.

Referring to the drawing, and more particularly to Fig. 1, the plunge-bath 10 is shown with one end, 11, shallower than the other. The bath is provided with a life-rail 13 of approved construction, around its

upper edge. Both ends of the bath are provided with hand-holds 14, which assist the bathers when entering and when leaving the tank. At both ends ladders or steps 15 are provided, which consist each of a plurality of superposed step-members 16, having each a pocket or depression 17 therein adapted to receive the foot or hand of the bather and afford a secure grip thereto. The foot when placed in the pocket is supported at the forward portion by the bottom or tread 18 of the pocket, and the foot is supported at the arch on an upright rest 19 at the front of the pocket; which rest also serves when the pocket is used by the hand instead of the foot, as a hold for the fingers. The tread slopes from both sides toward the center of the same, and at the center is the upper end of a drain-opening 20, the lower end of which is at the outside of the step-member. Water dripping from the feet and hands of users, or splashed into the pocket, is thereby drained out, and the pocket is kept free of water and constantly washed by use. When the step-members are placed at the water-level, water enters the pocket through the opening 20, and flushes the same. This is shown in Fig. 2, in which the water of the tank is indicated at 21.

In the form of step-member shown in Figs. 4, 5, 6 and 7, the pocket 27 is made larger than in Figs. 2 and 3, and for affording a firm footing the tread 24 is made of uniform height from side to side of the pocket. For causing the proper drainage of water off of the tread, the same is forwardly inclined to such extent as to cause the water to freely run off, but not to such extent as to materially affect the security of the foot when placed thereon. Such inclination causes the water to drain into a channel 23 which is provided at the forward portion of the step-member immediately back of the front vertical rest 24. Said channel is provided with sloping sides 25, which conduct the water to a drain-opening 26 which leads the drainage to the outside of the step-member. The depth of the channel 23, and its width, are such that the fingers of the bather are freely accommodated therein and are permitted to grasp the rest 24 without obstruction. Thus whether used by foot or by hand, the step-member gives reliable support.

In Fig. 8 is shown another arrangement, in which the uppermost member is made in-

tegral with the life-rail 30. By making these parts integral, it is possible to give both parts the necessary strength, while at the same time reducing the vertical distance from the step to the life-rail, so that the bather may without extra effort step from the topmost step over the life-rail.

The members are arranged as shown in Fig. 1, preferably at each end of the plunge-bath tank, and are superposed on each other, so as to form a ladder or series of steps in the wall of the tank, so that the bathers may place feet and hands in the same and thereby find convenient entrance and exit from the bath.

By placing the feet in the step-members, and grasping the life-rail by hand, bathers may easily rest and support themselves above the water. It is also preferable to arrange a series 28 of these members on a horizontal line approximately at water level, extending from the deep to the shallow portion of the tank, thus affording a safety-device enabling bathers to find support when exhausted, and to make their way from the deep to the shallow portion of the tank.

We have shown several forms of step-members, but it is obvious that other constructions may be employed, without departing from the spirit of the invention.

We claim:

1. In a plunge-bath, a plurality of members superposed on each other and each having a pocket, said members having each a tread for the forward portion of the foot, and a rest for the middle of the same, and a drain-channel between said tread and rest.

2. A plunge bath block having a complete foot pocket provided with a central drain opening and drain chambers sloping laterally in opposite directions toward said drain opening.

3. A plunge bath having a hand hold or life rail extending along its top and a series of foot pockets arranged along one side substantially parallel with the life rail at a distance therefrom which permits the bather to place his feet in the pockets while grasping the life rail.

4. A plunge bath member having a complete pocket and provided with a lip extending upward from the top of the pocket flush with the outer face of the member and adapted to serve as a hand hold.

5. A plunge bath member having a pocket provided with a tread for the forward portion of the foot, a rest for the middle thereof and a drain channel between said rest and tread.

6. A plunge bath member having a complete foot pocket provided with an inner tread for the forward portion of the foot and a lip at the outer edge thereof adapted to serve as a rest for the middle portion of the foot or as a hand hold.

In testimony, that we claim the foregoing as our invention, we have signed our names in presence of two subscribing witnesses.

JOHN FRANCIS BOORAEM.
GABRIEL E. ROHMER.
